(57) **CLAIM**

The ornamental design of a staple packaging, as shown and described.

DESCRIPTION

FIG. 1 is a perspective view of a staple packaging as seen from the top, front and left sides.

FIG. 2 is a left side elevation view thereof.

FIG. 3 is a top plan view thereof.

FIG. 4 is a front elevation view thereof, the rear elevational view being a mirror image.

FIG. 5 is a bottom plan view thereof; and,

FIG. 6 is a perspective view similar to FIG. 1 wherein the broken line disclosure is for environmental purposes only and does not constitute a part of the claimed design.
